VALVE GRINDING MACHINE

Application filed November 11, 1929. Serial No. 406,267.

My application relates to improvements in valve grinding machines. The objects of my invention are:

- To provide a simple, easily operated 5 grinder for grinding valves for internal combustion engines and other similar valves;
To provide a valve grinder which can be manufactured at low cost and will be simple and easy to operate;

10 To reduce the number of parts required for an efficient grinder;

To provide simplified means for revolving a valve to be ground in a fixed position and for causing the contacting part of the grinding wheel to travel across the face of the surface to be ground in a substantially horizontal path, the valve stem in the meantime revolving in a horizontal plane.

I attain these objects by the means illustrated in the accompanying drawings, in which

Figure 1 is a plan view of my machine, but showing the various parts in section;

Figure 2 is an end elevation;

25 Figure 3 is a partial plan view showing parts in section and showing an alternate form of connecting the grinding shaft and the chuck shaft;

Figure 4 is a detail end view of a tool holder for holding a diamond dressing tool;

Figure 5 is a plan view of same.

Similar numerals refer to similar parts throughout the several views.

35 My machine comprises a flat base, 1, preferably five-cornered, although it may be of any desired shape, and with the housing, 2, bearing, 3, bearing support, 4, and bosses, 6 and 6', preferably cast or otherwise formed integral therewith.

40 In the bosses 6 and 6', I mount a pivot shaft, 7. The boss, 6', is threaded and the pivot shaft, 7, has its rear end threaded as at 27 and has a hand-wheel 28, rigidly secured thereto by which it may be turned and when turned, the action of the threaded part upon the threads in the boss, 6', will cause the pivot shaft to move longitudinally of the base.

45 A saddle, 8, having hubs, 8a and 8b, formed integral therewith, is pivotally mounted upon the pivot shaft, 7. Collars, 25 and 26,

are secured to the shaft by pins, 25a and 26a, or other suitable means, adjacent the hubs, 8b and 8a, and as the shaft moves longitudinally, these collars carry the saddle, 8, along with the shaft. Upon the saddle, 8, I secure 55 an electric motor 18 by set screws, 8c, or other suitable means. This motor is provided with an extended shaft, 17, upon the front end of which I mount by press-fit or other suitable means, a threaded sleeve, 20a, having a 60 flange, 20, formed integral therewith.

This sleeve is externally threaded with threads which fit an internally threaded sleeve, 19, and the grinding wheel, 16, being mounted upon the sleeve, 20a, is firmly secured 65 thereon by the sleeve, 19.

The rear end of the shaft, 17, is mounted in a bushing, 17a, at the rear of the motor and is bored out to receive one end of a cable or flexible shaft, 22, which may be secured 70 thereto by a press-fit, by sweating, by a pin or other suitable means.

The cable or flexible shaft, is covered with a housing, 24, which is connected to the motor housing at the rear end thereof by a sleeve, 75 23, with threads, 23a, to secure it to the housing.

The bearing, 3, extends at an angle of 45° or other desired angle, to the pivot shaft, which is parallel to the motor shaft. A bushing, 42, is mounted therein and a chuck shaft, 43, is revolvably mounted within the bushing. The front end of the chuck shaft, 43, is tapered and forms an arbor to receive the chuck, 37.

80 The chuck, 37, may be of any of the ordinary types in common use and I make no claim for any particular type of chuck. The chuck, 37, has jaws, 37a, in which the shank or stem, 35, of the valve to be ground, may 85 be inserted.

Upon the rear end of the chuck shaft, 43, I mount a relatively large gear wheel, 30, which is preferably secured in place by threading the end, 29, of the chuck shaft, 43, and placing a nut, 29a, thereon. The gear wheel, 30, may be secured to the chuck shaft, 43, in any desired manner.

Integral with the base, 1, and housing, 2, I cast a bearing, 2a, in which a jack shaft, 32, 100

is mounted and in which it is secured by a collar, 33, and nut, 32a. Upon the rear of the jack shaft, 32, I mount a relatively small gear, 31, in mesh with the gear, 30. The 5 jack shaft, 32, extends through the gear, 31, and its rear end is enlarged into a head, 31a, which is hollow and in which one end of the cable or flexible shaft is rigidly secured. The corresponding end of the cable housing, 24, 10 is secured to the housing, 2, by a threaded sleeve, 34. The intermediate portion of the flexible cable is supported by an arm, 38, having a vertical portion, 39, extending through the upper portion of the base and bent at a 15 right angle to form an extension, 40, which bears against the under side of the top portion of the base and holds the arm, 38, in substantially horizontal position. The outer end of the arm, 38, is formed into a hook, 41, 20 to aid in holding the cable housing, 24, securely.

In order to grind valves to the best advantage, it is necessary to revolve the valves and that the portion of the valve, in contact with 25 the grinding wheel, should revolve in a direction opposite to the contacted portion of the grinding wheel. In the arrangement shown in Figure 1, as the grinding wheel revolves to the right, the valve being driven through the gears, 30 and 31, and the flexible shaft, 22, will also revolve to the right.

It is also advisable to revolve the grinding wheel at a considerably more rapid rate than the valve being ground.

35 This is accomplished in Figure 1 by the gears, 30 and 31, which act to reduce the speed of the valve.

It is also accomplished in a measure by 40 using a grinding wheel, 16, of materially greater diameter than the head, 36, of the valve.

In Figure 3 I have shown an alternative arrangement which is even simpler than the arrangement shown in Figure 1. In Figure 45 3 I have shown a sleeve-like connecting piece, 47, rigidly mounted upon the front end of the motor shaft, 17, with a flange collar, 48, to lock the grinding wheel securely between the flange collar and a fixed flange 50 upon the connecting piece, 47. One end of the cable or flexible shaft, 46, is rigidly secured to the connecting piece, 47, and the cable or flexible shaft, 46, is then carried around through suitable openings, 49, in the 55 base, to the rear end of the chuck support and united to the rear end of the chuck shaft, 43, by a press-fit or other suitable means.

The cable housing, 45, may be suitably 60 united to the connecting piece, 47, by the threaded sleeve, 44, and to the chuck shaft bearing by a threaded sleeve, 47a.

I prefer to use the cupped form of grinding wheels as that will give the most accurate results, but any suitable form of grinding wheel may be utilized. I prefer to have the

thickness of the grinding face of the cupped wheel a little greater than the width of the valve face to be ground, but it is obvious that these proportions may be varied to suit the requirements of any particular case or the desires of any individual operator. With a grinding face from $\frac{1}{4}$ to $\frac{3}{8}$ of an inch in width, but a very slight movement of the motor and grinding wheel is necessary to feed the wheel entirely across the ground face of the valve.

While the motor saddle may be pivoted at any point, I prefer to so construct my machine that the motor shaft will normally lie slightly below the horizontal plane in which the valve shaft revolves, and the grinder will then be fed across the face of the valve manually by grasping the handle, 21, in one hand and drawing it toward the housing, 2.

With the motor shaft located and pivoted as shown, the face of the cupped wheel will then be drawn across the beveled face of the valve in a slight arc which is almost horizontal, the point of contact being slightly above the horizontal axis of the chuck shaft at the middle of the travel of the grinder and being slightly below the level of the axis of the chuck shaft at both ends of its travel.

In Figures 1 and 2 I have shown the grinder at the middle of its travel. When released from the pressure of the hand, the motor saddle will descend until its rests upon the adjacent portion of the base.

The drawings show my machine somewhat reduced from normal size. The normal size should be made sufficient for the ordinary run of valves and extra sizes may be made for extra large valves, if desired.

The threaded portion, 27, of the shaft, 7, provides means for adjusting the longitudinal position of the motor sufficiently to meet all ordinary requirements, but of course, can be varied as desired to meet particular cases.

In the use of grinding wheels, it is necessary to true the grinding faces from time to time. For this purpose, I have devised a dressing tool which comprises a body, 12, having a shank, 15, slidably mounted therein, with its point fitted with a diamond. A set screw, 14, is threaded into the body, 12, about which the shank 15, can be locked in any desired position of adjustment. A shank, 11, is formed integral with the body, 12, adapted to enter the opening 11a. In an extension, 9, formed upon the upper end of the boss, 6, a set screw is threaded by which the shank, 11, can be locked therein.

In the operation of my device, the valve stem, 35, is placed in the jaws, 37a, of the chuck in the usual manner. The hand-wheel, 28, is then turned until the face of the grinding wheel, 16, has reached the proper position relative to the valve head, 36. The motor is then started and the motor and grinding wheel are manually swung upon the

pivot shaft, 7, until the face of the grinding wheel passes the beveled face of the valve head. This should be repeated several times and the grinding wheel may be fed up closer and closer to the valve until the proper face has been ground thereon. The motor may then be stopped and the valve taken out and replaced and the operation repeated.

When necessary to dress the grinding wheel, the valve is removed from the chuck and the dressing tool shown in Figure 4 inserted in the extension, 9, of the boss, 6, and locked in the desired position by the set screw 10. The shank, 15, is then moved to the desired position and locked by the set screw, 14. The motor is then started and the grinding wheel moved to the desired point longitudinally by the hand-wheel, 28. The motor and grinding wheel are then swung upon the pivot shaft, 7, and the face of the grinding wheel moved slowly past the point of the diamond of the dressing tool.

I prefer to use a rather fine thread upon the shaft, 7, so that the grinding wheel may be fed up to the valve and to the dressing tool very slowly.

The weight of the motor and saddle will assist the operator in moving the grinding wheel steadily and firmly.

It is obvious that the motor and grinding wheel may be pivoted at a point directly under the motor shaft or at such other point as may be desired, but I prefer to pivot same substantially as shown so as to avoid the vertical travel which would necessarily take place if pivoted at a point farther from the valve.

For clearness of reference in the claims, except when otherwise indicated, I refer to the shaft, 7, as the pivot shaft; to the shaft, 17, as the motor shaft or grinder shaft; to the shaft, 43, as the chuck shaft or valve shaft or as a secondary shaft; to the shaft, 32, as a jack shaft; and to the cable or flexible shaft, 46, as a flexible shaft.

The term, "flexible shaft" is intended to cover a chain, a cable, a plurality of shaft sections united by universal joints or any other form of shaft-like connection which will transmit rotary motion directly and which may be flexed so as to permit relative movement of a pair of rigid shafts driven thereby.

I claim:

1. A valve grinding machine comprising a base, a motor saddle pivotally attached to the base, a motor secured upon the saddle, a handle united to the motor housing, a grinding wheel mounted upon one end of the motor shaft, a bearing united to the base, a valve shaft mounted in the bearing at an acute angle to the motor shaft, means secured upon the valve shaft adapted to receive and hold the stem of a valve to be ground, a flexible shaft coupled directly to the motor shaft and

valve shaft, and means for adjusting the motor longitudinally.

2. In a valve grinding machine, a base, hubs united to the base, a pivot shaft seated in the hubs, with means for turning the pivot shaft united to one end thereof, one of said hubs and the portion of the shaft adjacent thereto being correspondingly threaded, a saddle pivotally mounted upon the pivot shaft, sleeves secured upon the pivot shaft adapted to prevent the relative longitudinal movement of the saddle thereon, a motor mounted upon the saddle and having a motor shaft extending beyond the motor housing at one end thereof, and a grinding wheel rigidly secured upon the extended end of the motor shaft.

3. In a valve grinding machine, a base, hubs united to the base, a pivot shaft seated in the hubs, with means for turning the pivot shaft united to one end thereof, one of said hubs and the portion of the shaft adjacent thereto being correspondingly threaded, a saddle pivotally mounted upon the pivot shaft, means secured upon the pivot shaft adapted to prevent the relative longitudinal movement of the saddle thereon, a motor mounted upon the saddle and having a motor shaft extending beyond the motor housing at one end thereof, and a grinding wheel rigidly secured upon the extended end of the motor shaft.

4. In a valve grinding machine, a base, hubs united to the base, a pivot shaft seated in the hubs with means for turning the pivot shaft united to one end thereof, one of said hubs and the portion of the shaft adjacent thereto being correspondingly threaded, a saddle pivotally mounted upon the pivot shaft, sleeves secured upon the pivot shaft adapted to prevent the relative longitudinal movement of the saddle thereon, a motor mounted upon the saddle and having a motor shaft extending beyond the motor housing at one end thereof, a grinding wheel rigidly secured upon the extended end of the motor shaft, and a socket in the base in front of the grinding wheel, and a removable dressing tool seatable in the socket.

In testimony whereof he affixes his signature.

HARRY J. CRINER.
